FLAME-PRODUCING MECHANISM

Louis V. Aronson, Newark, N. J., assignor to Art Metal Works, Inc., a corporation of New Jersey

Application October 11, 1934, Serial No. 747,855

11 Claims. (Cl. 67—4.1)

My invention relates to flame-producing mechanism operable by manual action to ignite a charge of fuel carried by a torch-forming member or the like.

5 In an important aspect, my invention relates to flame-producing mechanism which is efficient, simple from the mechanical viewpoint, and readily operable for the intended purpose.

In another important aspect, my invention has 10 reference to a novel and advantageous arrangement for securing the various parts of the aforesaid mechanism in assembled relation.

Various other objects, advantages and characteristics of my invention will become apparent 15 from the following detailed description.

My invention resides in the flame-producing mechanism, pyrophoric lighting mechanism, features and arrangements of the character herein-after described and claimed.

20 For an understanding of my invention and for an illustration of one of the many forms thereof, reference is to be had to the accompanying drawing, in which:

Figure 1 is an elevational view, partly broken 25 away, showing various parts of my novel mechanism in disassembled relation;

Fig. 2 is a vertical sectional view, partly in elevation, of my novel mechanism with the various parts in assembled relation;

30 Fig. 3 is a horizontal sectional view, partly in plan, and is taken on the line 3—3 of Fig. 1; and

Fig. 4 is a horizontal sectional view, partly in plan, and is taken on the line 4—4 of Fig. 1.

35 As shown on the drawing, the herein described mechanism comprises a frame arrangement formed from upper and lower plates 1 and 2, the upper plate 1 terminating in a peripheral, depending flange 1a. For the purpose of holding 40 these two plates in fixed, parallel relation with respect to each other, a plurality of sleeves or rods 3 may be disposed vertically therebetween, these sleeves or rods being secured to the respective plates by screws 4.

45 Suitably secured to the upper surface of the plate 1 is a housing 5 which comprises spaced vertical walls in which a horizontal supporting member 6 is anchored. Rotatably disposed on this member 6 are the side-by-side wheels 7 and 50 8, the wheel 7 being roughened or serrated on its peripheral surfaces and the wheel 8 being a ratchet wheel, these two wheels being secured together in any suitable manner so as to be rotatable together as a unit. Coactable with the serrated wheel 7 is a pyrophoric element 9 which

is carried by and projects from the upper end of a tube 10 extending downwardly through the plates 1, 2 and being secured thereto in any suitable manner. Disposed interiorly of the tube 10 is a helical spring 11 which is maintained under compression by a cap member 12 threaded into the lower end of said tube 10, the spring 11 engaging the pyrophoric element 9 and holding the same in engagement with the serrated wheel 7.

As clearly appears from a consideration of Figs. 1 and 4, the lower plate 2 comprises a pair of spaced, upstanding bracket arms 2a which support a horizontal member 13. A lever 14 is freely oscillatory on the member 13 and this lever is 15 biased in a clockwise direction, Fig. 2, by a spring 14c which is coiled around said member 13. The upper section 14a of said lever 14 extends through a slot in the upper plate 1, the upper end of said lever section 14a having pivoted thereto a 20 ratchet bar 15 which is biased in a clockwise direction, Fig. 2, by a spring 16 whereby the ratchet teeth on the bar 15 are held in engagement with the ratchet teeth of the wheel 8.

The lower lever section 14b of the aforesaid lever, immediately adjacent its extreme end, carries a transverse member 17 which extends through a member 18 slidably disposed interiorly of a sleeve 19 mounted for vertical reciprocatory movement in an opening formed in the aforesaid plate 1. As is clearly shown on the drawing, the member 19 is of substantially less length than the member 18 so that a helical spring 20 may be disposed in the sleeve 19 between the upper end thereof and the upper surface of said member 18. Further, as clearly indicated in Figs. 1, 2 and 4, the sleeve 19 is provided with oppositely disposed elongated slots through which the transverse member 17 extends so that there may be 30 relative movement of the sleeve 19 with respect to the lever section 14b while the latter remains stationary.

The aforesaid lever section 14b carries a transversely extending latch pin 21 with which is adapted to engage the upper notched end of a 45 lever section 22a, the body of which is pivoted at 23 to an upstanding ear of the lower plate 2. This lever is suitably biased in a clockwise direction, as by a spring 24, one end of which engages the lower lever section 22b to which at 50 one end is pivoted a rod 25 which extends upwardly through the upper plate 1.

The aforesaid sleeve 19 terminates above the upper plate 1 in a cap-shaped member 19a provided with a centrally-disposed upwardly facing 55

depression 19b. As hereinafter described, the flange of the cap-shaped member 19a, upon depression thereof, is adapted to engage and thrust downwardly the rod 25 whereby the notched upper end of the lever section 22a is swung in a counter-clockwise direction from the position shown in Fig. 1.

For operating the sleeve 19 in the manner described, there is provided a torch-forming member T which comprises a stem 26 carrying a lower fixed sleeve 27 provided with one or more openings 27a which expose sections of a wick 28 axially disposed in said stem 26 and the sleeve 27. The torch-forming member T further comprises a handle section 29 below which is disposed a bearing section 30 utilizable as hereinafter described.

In accordance with my invention, there is provided a fuel casing F which comprises a receptacle 31 formed from sheet material to which is secured a lower weighted rim section 32. As shown, the receptacle 31 contains a mass of absorbent material 33 and the fuel may be introduced thereto through any suitable opening 25 such as the one closed by the closure cap 34. Further, as shown, the receptacle 31 is provided with a vertical passage as defined by a tubular member 35 into which the lower end of the aforesaid tube 10 is adapted to extend. Still further, the fuel casing F carries an upstanding tubular member 36 which defines a vertical passage communicating with the interior of the receptacle 31 as clearly shown in Fig. 2.

As shown on the drawing, M represents the main casing or the casing for the above described mechanism carried by the plates 1 and 2. In the example illustrated, this casing is nothing other than a rectangular shell open at the top and bottom thereof, the interior dimensions thereof corresponding in configuration with and being only slightly larger than the above described lower plate 2.

To assemble the device herein disclosed, the above described frame arrangement is so moved that the lower plate 2 enters and passes almost entirely through the casing M, the upper plate 1 and its flange 1a seating upon and around the upper edge of said casing M. While thus held, these parts are brought into assembled relation with respect to the fuel casing F.

As indicated on the drawing, each of the plates 1 and 2 is provided with an opening, these openings being vertically aligned and of such diameter that the upstanding tubular member 36 of the fuel casing F may readily pass therethrough. Accordingly, the casing M may readily be seated upon the fuel casing F after the former has been associated with the frame arrangement comprising the plates 1 and 2 as described above. As shown in Fig. 4, the upper surface of the fuel casing comprises a pair of spaced, upstanding lugs 37 upon which one end of the lower plate 2 seats, these lugs being suitably positioned so that they serve to locate the casing M when it is seated on the fuel casing F.

When the parts have been assembled as described above, they are positioned substantially as illustrated in Fig. 2. As will be noted, the lower end of the tube 10 is received in the passage defined by the tubular member 35 and the tubular member 36 extends upwardly through the vertically aligned openings of the plates 1 and 2, said member 36 terminating above the plate 1 in a screw-threaded section which has a nut 38 threaded thereto.

A particular feature of the invention resides in the provision of an arrangement of the character last described. The single nut 38, when threaded to its lowermost position on the tubular member 36, holds the frame plate 1 in close engagement with the upper surface of the casing M. Accordingly, it results that said casing M together with the frame arrangement comprising the plates 1 and 2 are securely and firmly anchored on the fuel casing F, one end of the lower plate 2 seating upon the lugs 37 and the other end thereof engaging the lower surface of the tubular member 36. The parts when thus anchored in position are in condition for manual operation in the manner hereinafter described.

Obviously, an arrangement of the character described is particularly advantageous from the manufacturing viewpoint. The various mechanical parts may readily be assembled on the open frame comprising the plates 1 and 2 and this assemblage may subsequently be disposed interiorly of its enclosing casing and secured to its supporting base in the manner described above. Furthermore, when once assembled, the mechanism may readily be disassembled, should the occasion arise, merely by removal of the single nut 38.

As shown in Fig. 2, the hereinbefore described torch-forming member T is supported by the tubular member 36. That is, the bearing section 30 of said member T engages and forms a sealed joint with the upper interior surface of the tubular member 36, and the stem 26 together with the sleeve 27 thereof extend downwardly within said member 36. The sleeve 27 of the torch-forming member T is received interiorly of the fuel casing F with the wick 28 in fuel-transferring relation with respect to the fuel therein and, if desired, it shall be understood that the fuel casing may contain a tubular structure which receives the sleeve 27 such, for example, as disclosed in my pending application Serial No. 719,640, filed April 9, 1934.

The operation is as follows:

The various parts carried by the frame arrangement comprising the plates 1 and 2 are shown in their normal respective positions at the upper part of Fig. 1. When the lighting mechanism is to be operated, the torch-forming member T is removed from its holder which is constituted by the tubular member 36 and the lower end of said member T is seated in the depression 19b of the sleeve 19. In response to downward thrusting movement imparted to said member T, the sleeve 19 is caused to partake of similar downward movement whereby the spring 26 is compressed. This compressing action necessarily happens, at this time, because the lever 14 is locked in the position shown in Fig. 1 by the latching lever 22a, 22b and, accordingly, the member 18 remains stationary during initial downward movement of the sleeve 19.

Eventually, during continued downward movement of the aforesaid sleeve 19, the flange 19a thereof engages the rod 25 to thereby impart counter-clockwise movement, Fig. 1, to the lever 22a, 22b. By this action, the notched end of said last named lever is disengaged from the pin 21. When this happens, the lever 14 becomes free to swing in a counter-clockwise direction from its position shown in Fig. 1 to that shown in Fig. 2 and said lever 14 immediately swings in such counter-clockwise direction under the influence of the energy stored in the spring 26 which expands suddenly when the lever 14 is released as

just described. In response to such counter-clockwise movement of the lever 14, a step of rotative movement is imparted to the wheels 7 and 8, the wheel 7 coacting with the pyrophoric element 9 to produce a shower of sparks which pass through the adjacent open side of the housing 5, and then toward and above the cap-shaped member 19a of the sleeve 19. Inasmuch as the lower end of the torch-forming member is held 10 in engagement with said cap-shaped member 19a at this time, it follows that the fuel carried by the exposed sections of the wick 28 is ignited by the sparks to thereby produce a freely burning flame at the lower end of said member T. This 15 member may now be removed from the sleeve 19 and used for any desired igniting purpose such, for example, as the ignition of pipes, cigarettes, candies, etc., etc.

When the member T is removed from the sleeve 20 19 as just stated, the spring 14c, which was placed under tension by the expansion of spring 20, becomes effective to restore the various parts to their normal, respective positions. That is, said 25 spring 14c swings the lever 14 in a clockwise direction from the position thereof shown in Fig. 2 to that shown in Fig. 1 to thereby cause the sleeve 19 to move upwardly to the position shown in Fig. 1. During such movement of the lever 14, the ratchet bar 15 moves from left to right with 30 respect to the ratchet wheel 8, the teeth thereof idling with respect to the ratchet teeth of said wheel 8 which remains stationary at this time due to the thrusting engagement of pyrophoric element 9 with the wheel 7. When the lever 14 reaches its normal position as shown in Fig. 1, 35 the spring 24 becomes effective to swing the lever 22a, 22b in a clockwise direction from its position shown in Fig. 2 to that shown in Fig. 1 whereby the notched end of the lever section 22a 40 becomes reengaged with the latching pin 21. The parts are now in their normal positions ready for subsequent operation.

After the flame at the lower end of the torch-forming member T has served its intended purpose, the flame may be extinguished and said member T restored to its normal position as shown in Fig. 2.

While the invention has been described with respect to a certain particular preferred example 50 which gives satisfactory results, it will be understood by those skilled in the art after understanding the invention, that various changes and modifications may be made without departing from the spirit and scope of the invention and it is intended therefore in the appended claims to cover 55 all such changes and modifications.

What is claimed as new and desired to be secured by Letters Patent is:

1. In pyrophoric lighting mechanism, a fuel 60 casing, a main casing, and a mechanical operating assembly comprising a serrated member and a pyrophoric element coactable therewith said fuel casing detachably supporting said main casing and said operating assembly said operating 65 assembly being detachable as a unit from said main casing, said operating assembly coacting with said main casing to retain it on said fuel casing.

2. In pyrophoric lighting mechanism, a fuel 70 casing, a main casing, a mechanical operating assembly, said fuel casing detachably supporting said main casing and said operating assembly, said fuel casing comprising a member extending upwardly through said main casing, and means 75 coactable with said member for retaining said

fuel casing, said main casing and said operating assembly in assembled relation, said operating assembly comprising means which engage said main casing and prevent movement thereof with respect to said fuel casing when said fuel casing, 5 said main casing and said operating assembly are thus held in assembled relation.

3. In pyrophoric lighting mechanism, a fuel 10 casing, a main casing, a mechanical operating assembly, said fuel casing detachably supporting said main casing and said operating assembly, said fuel casing comprising a member extending upwardly through said main casing, and means coactable with said member for retaining said fuel casing, said main casing and said operating 15 assembly in assembled relation, said means comprising a single nut detachably threaded to said member for the purpose described, said mechanical operating assembly comprising means which engage said main casing and prevent movement 20 thereof with respect to said fuel casing when said fuel casing, said main casing and said operating assembly are thus held in assembled relation.

4. In pyrophoric lighting mechanism, a fuel 25 casing, a main casing, a mechanical operating assembly comprising a sparking unit said fuel casing supporting said main casing and said operating assembly being detachably supported on said main casing, said fuel casing comprising a member extending upwardly through said main 30 casing, and means coactable with said member for retaining said operating assembly and said main casing in assembled relation, said member being tubular and adapted to receive a torch utilizable for actuating said sparking unit. 35

5. In pyrophoric lighting mechanism, a fuel 40 casing, a main casing, a mechanical operating assembly, said fuel casing supporting said main casing and said operating assembly being detachably supported on said main casing, said fuel casing comprising a tubular member extending upwardly through said main casing, and means coactable with said member for retaining said operating assembly and said main casing in assembled relation, said tubular member serving 45 as a holder within which is received the torch arrangement of said lighting mechanism.

6. In pyrophoric lighting mechanism, a fuel 50 casing, a main casing positioned on said fuel casing, a mechanical operating assembly disposed within said main casing, said mechanical operating assembly being detachable as a unit from said fuel casing and said main casing, said mechanical operating assembly comprising a frame, a spark-producing unit carried by said 55 frame, a lever interiorly of said frame for actuating said unit, and a member carried for vertical reciprocatory movement by said frame for operating said lever.

7. In pyrophoric lighting mechanism, a fuel 60 casing, a main casing positioned on said fuel casing, a mechanical operating assembly disposed within said main casing, said mechanical operating assembly being detachable as a unit from said fuel casing and said main casing, said mechanical 65 operating assembly comprising a frame, a spark-producing unit carried by said frame, a lever interiorly of said frame for actuating said unit, a member carried for vertical reciprocatory movement by said frame for operating said lever, 70 a latch pivoted to said frame for controlling movement of said member, and a member slideable in said frame for operating said lever.

8. In pyrophoric lighting mechanism, a fuel 75 casing, a main casing positioned on said fuel

casing, a mechanical operating assembly disposed within said main casing, said mechanical operating assembly being detachable as a unit from said fuel casing and said main casing, means for retaining said fuel casing, said main casing and said mechanical operating assembly in assembled relation, and means for preventing movement of said main casing with respect to said fuel casing.

9. In pyrophoric lighting mechanism, a fuel casing, a main casing positioned on said fuel casing, said main casing being a shell formed from sheet material and being open at the respective opposite ends thereof, a mechanical operating assembly disposed within said main casing, 10 said mechanical operating assembly being detachable as a unit from said fuel casing and said main casing, means for retaining said fuel casing, said main casing and said mechanical operating assembly in assembled relation, and 15 means for preventing movement of said main casing with respect to said fuel casing.

10. In pyrophoric lighting mechanism, a fuel casing having a passage extending vertically therethrough, a main casing positioned on said fuel casing, a mechanical operating assembly disposed within said main casing, a spark-producing unit associated with said mechanical operating assembly and comprising a pyrophoric metal tube extending downwardly through said passage,

said mechanical operating assembly being detachable as a unit from said fuel casing and said main casing, means for retaining said fuel casing, said main casing and said mechanical operating assembly in assembled relation, and means for preventing movement of said main casing with respect to said fuel casing.

11. A lighter construction, comprising a base portion embodying a fuel container, a casing thereon, a cover member for said casing, a pyrophoric sparking mechanism assembly mounted on said cover member, tubular means fixed to said fuel container and extending upwardly therefrom within said casing and through said cover member, said tubular means comprising a 10 conduit for introducing fuel into said container, means at the top of said tubular means for removably retaining said cover member with the mechanism thereon as well as said casing, in assembled relationship with said base portion, 15 and a removable torch member adapted to be received in said tubular means, said torch member having a wick portion at its lower end adapted to absorb fuel from said fuel container, said torch being removable for application to said 20 mechanism to operate the latter for ignition of said wick portion.

LOUIS V. ARONSON.
